POWER UNIT

Felber Maasdam, 1432 N. Ontario, Burbank, Calif.
Filed June 23, 1960, Ser. No. 38,311
5 Claims. (Cl. 74—142)

This invention relates to improvements in power units or pulling devices of the type in which rotary motion is imparted to a cable winding drum through pawl and ratchet mechanisms, the latter being operated by an oscillatory lever.

More particularly, the invention relates to a reversible hand operated pulling unit having simplified and improved means for controlling the retrograde movement of the winding drum when the latter is under load.

A primary object of the invention is to provide a power unit of the above-mentioned character having novel and simplified cam and spring means associated with the feed or lever pawl for rendering the same active and inactive with respect to the ratchet teeth of the winding drum, said means enabling the lever pawl to coact with the holding pawl for the winding drum in a simplified and more efficient manner.

Other objects and advantages of the invention will be apparent during the course of the following description.

In the accompanying drawings forming a part of this application and in which like numerals are employed to designate like parts throughout the same:

FIGURE 1 is a perspective view of the power unit according to the invention in its entirety.

FIGURE 2 is an enlarged fragmentary side elevation of the power unit in one operative position.

FIGURE 3 is a plan view of the unit shown in FIGURE 2.

FIGURE 4 is an enlarged fragmentary side elevation of a feed pawl control lever and associated elements.

FIGURE 5 is a fragmentary perspective view of the feed pawl and control means therefor and associated elements.

FIGURE 6 is a fragmentary vertical section through one portion of the operating lever and showing the control cam and lever for the feed pawl.

FIGURES 7, 8 and 9 are fragmentary side elevational views illustrating the coaction between the feed and holding pawls for the cable winding drum during retrograde movement of the latter and further illustrating the novel means for rendering the feed pawl active and inactive.

The general construction of the power unit is disclosed in prior United States Patents 2,506,029 and 2,669,426, among others, and the general construction needs only to be described briefly herein.

With reference to the drawings, wherein for the purpose of illustration is shown a preferred embodiment of the invention, the numeral 10 designates generally a rigid frame or yoke including spaced parallel arms 11 and opposite end portions 12, having heads 13 rigid therewith. Bifurcated connector elements 14 are swiveled to the heads 13 and carry anchor hooks 15, pivoted thereto at 16.

An operating handle or lever 17 is provided, including spaced arm extensions 18, engaging inwardly of the frame sides 11 and pivoted thereto at the longitudinal centers thereof by means of a transverse bolt 19, rigid with the frame 10.

A cable winding drum 20 for pulling cable 21, having hook 22, is journaled for rotation upon the bolt 19, between arm extensions 18. The drum 20 is provided at one end with the usual ratchet teeth 23 for coaction with the feed and holding pawls to be described. A guide element 24 for cable 21 is fixedly secured to the frame 10,

2

as shown, and an anti-backlash guard 25 for the cable wound upon the drum 20 is also provided in surrounding relation to one side portion of the drum.

The construction thus far described is largely conventional, and shown in the mentioned prior patents, and a more detailed description of the general construction of the power unit is therefore believed to be unnecessary herein.

A driving or feed pawl 26 for the drum 20 is pivotally mounted at 27 between the arm extensions 18 of operating lever 17, and the feed pawl 26 is formed integral with a transverse sleeve 28, which receives the pivot element 27 rotatably. A pawl operating extension 29, formed integral with the sleeve 28, extends adjacent to one side of the operating lever 17, intermediate the ends of the operating lever. The feed pawl 26 is positioned for coaction with the ratchet teeth 23, as shown.

A holding pawl 30 for the winding drum 20 includes a transverse sleeve portion 31, rotatably mounted upon a transverse pin 32, extending between and rigid with the frame portions 11, near corresponding ends of the same. The holding pawl 30 is positioned for coaction with the ratchet teeth 23, as shown. The holding pawl 30 is biased toward engagement with the ratchet teeth 23 by a torsional coil spring 33, surrounding the sleeve portion 31 and having one end anchored to the frame 10 at 34, and its other end attached to an operating extension 35 of the holding pawl at 36. A spring loaded holding pawl lifting element or plunger 37 is bodily mounted upon the holding pawl 30 for coaction with the feed pawl 26 in a manner to be described, during retrograde movement of the winding drum 20 in a step-by-step manner.

Means forming an important feature of the invention are provided for rendering the feed pawl 26 active and inactive with respect to the ratchet teeth 23 and to facilitate the coaction between the feed and holding pawls during the step-by-step retrograde movement of the winding drum. This means comprises a substantially cylindrical cup-like cam 38, mounted for rotation upon one converging portion 39 of one arm extension 18 of the operating lever 17. The cam 38 is rigid with a stud element 40, rotatable within an opening 41 of arm portion 39, and an operating lever 42 for the cam 38 is rigidly secured to the rotatable stud 40 for rotation therewith and with the cam 38.

A coil spring 43 has a forward longitudinal extension 44 anchored at 45 to a lug 46 carried by the feed pawl operating extension 29. A rear longitudinal extension 47 carried by the spring 43 engages through an opening 48 in the forward portion of the peripheral wall 49 of cam 38. The spring extension 47 extends rearwardly across the cup-like cam 38, generally diametrically, and has its rear terminal portion 50 slidably engaging an approximately semi-circular curved peripheral cam portion or wall 51, as shown.

The edge 52 of the circumferential cam portion 51 is curved so as to slope gradually in opposite directions from a central high portion 53, toward low end portions 54, terminating at positive stops 55, formed upon the forward peripheral wall portion of the cam. Thus, when the cam 38 is turned by the operating lever 42 upon the axis of the stud 40, the spring extension 50 is adapted to ride over the curved or sloping cam edge 52 from one low cam portion 54 to the opposite low cam portion 54, in either of which positions the spring extension engages one of the stops 55. Intermediate the low portions 54 of the cam, the spring extension 50 passes over the high portion 53 of the cam edge 52. As this action takes place, the spring 43 attached to the feed pawl 26 at 45 is shifted from one side to another beyond dead center, and the spring 43 is tensioned to shift the feed pawl 26

to the inactive position or out of engagement with the ratchet teeth 23 in one extreme adjusted position of the cam 38, and to shift the feed pawl 26 to the active or driving position with respect to the teeth 23 in the other extreme adjusted position of the cam 38. As shown in FIGURE 4, the words "up" and "down" may be applied at 55' and 56' respectively to the outer face of the lever portion 39. When the cam operating lever 42 is shifted to the "up" position, FIGURE 4, the driving pawl 26 is rendered active with the teeth 23, as when a load is being lifted up with the cable 21. When the cam operating lever 42 is shifted to the "down" position, FIGURE 4, the pawl 26 is lifted and rendered inactive with respect to the teeth 23, as when the load on the cable 21 is being lowered in a step-by-step manner.

The power unit may be arranged in any position during use, such as vertically or horizontally, and the unit is anchored to some fixed object by one of the hooks 15. The cable hook 22 is attached to the load. When it is desired to pull the load by winding the cable 21 on the winding drum 20, the cam 38 is adjusted by its lever 42 to render the pawl 26 active with the teeth 23. The operating lever 17 is now swung by hand in the direction of the arrow in FIGURE 2, and the feed or driving pawl 26 will engage one of the teeth 23 on the drum for turning the later and pulling the cable in the direction of the arrow to wind it upon the drum. The holding pawl 30 will merely trip over the teeth 23 during this cable winding operation and the spring 33 of the holding pawl will yield to permit this action. The spring 33 will however maintain the holding pawl active with the teeth 33 so that the holding pawl will lock the drum 20 against retrograde movement each time the operating lever 17 is swung in the direction opposite to the arrow in FIGURE 2, prior to winding another length of the cable upon the drum. During retrograde movement of the lever 17, the spring 43 will yield to allow the pawl 26 to trip over the teeth 23 during retrograde movement of the lever 17.

When it is desired to pay out the cable 21 under load in the direction opposite to the arrow in FIGURE 2, and entailing step-by-step retrograde movement of the drum 20, the following procedure is followed, with particular reference to FIGURES 7 through 9 of the drawings.

The feeding pawl 26 is first rendered inactive with respect to the teeth 23 by shifting the cam lever 42 to the "down" position, thus elevating the feed pawl from engagement with the ratchet teeth 23. The operating lever 17 is then swung through an arc in the direction of the arrow, FIGURE 7, until the inactive pawl 26 engages the lifting plunger 37 of holding pawl 30. When this occurs, further movement of the lever 17 in the direction of the arrow, FIGURE 7, will disengage the holding pawl 30 from the ratchet teeth 23 of the drum, and the spring associated with the plunger 37 is strong enough to overcome the action of the holding pawl spring 33, for rendering the holding pawl inactive.

With reference to FIGURE 8, as the feeding pawl 26 lifts the holding pawl 30 from engagement with the ratchet teeth 23, due to continued movement of the lever 17 in the direction of the arrow, the reaction of the plunger 37 upon the pawl 26 will cause the spring 43 to yield, and pawl 26 will be shifted into engagement with the teeth 23 so as to serve for an instant as the holding pawl for the drum 20.

With reference to FIGURE 9, the operator now begins to return the operating lever 17 in the opposite direction, as shown by the arrow in FIGURE 9, and as this occurs, the drum 20 will revolve in the reverse or retrograde direction a distance equal to the space between one pair of the teeth 23, whereupon the holding pawl 30 will again become active under influence of its spring 33 and check the retrograde movement of the drum. In the meantime, the spring 43 again renders the feeding pawl 26 inactive, FIGURE 9, and the lever 17 is again shifted toward the holding pawl 30, FIGURE 7, and the same mode of operation takes place as illustrated in FIGURES 7 through

9, until the desired amount of step-by-step or tooth-by-tooth retrograde movement of the drum 20 is obtained.

It may now be seen that the provision of the single spring 43 only on the feeding pawl 26, for regulation by the novel cam 38 on the lever 17, accomplishes the plural purposes of rendering the feeding pawl 26 active and inactive, as desired, as well as facilitating the described co-action between the feed and holding pawls, as illustrated and explained above in conjunction with FIGURES 7 through 9 of the drawings. It is pointed out that by virtue of this arrangement it is entirely unnecessary to provide any torsion spring similar to the spring 33 on the feeding pawl 26, in addition to the single spring 43. The action of the cam 38 in shifting the spring 43 beyond opposite sides of dead center with respect to the feeding pawl 26 renders such pawl active and inactive when the lever 42 is shifted between its extreme adjusted positions, as regulated by the stops 55. When the pawl 26 is rendered inactive by the cam 38, the spring 43 is still able to function as in FIGURE 8, under influence of the plunger 37, to permit the pawl 26 to re-engage the teeth 23 at the moment during which the holding pawl 30 is inactive and the drum 20 is turning in a reverse direction in amount equal to the distance between one pair of the teeth 23.

It is to be understood that the form of the invention herewith shown and described is to be taken as a preferred example of the same, and that various changes in the shape, size and arrangement of parts may be resorted to, without departing from the spirit of the invention or the scope of the subjoined claims.

Having thus described my invention, I claim:

1. In a power unit of the character described, a frame for attachment to a fixed object, a cable winding drum journaled upon said frame for rotation, a swingable operating lever pivoted to said frame, ratchet teeth carried by said drum for driving the same, a holding pawl pivoted to said frame and resiliently biased toward active engagement with said ratchet teeth, a feeding pawl pivoted to said operating lever and engageable with said ratchet teeth to rotate said drum when the operating lever is swung in one direction, a coil spring connected with said feeding pawl and having an end longitudinal extension, a cup-like cam rotatably mounted upon said operating lever and including an operating part, said cam having a peripheral wall provided with an opening receiving said spring extension, said spring extension extending generally diametrically of said cam, said cam having a circumferential peripheral cam portion including a central high part and end low parts having sliding engagement with said spring extension, and stop elements on said cam adjacent said low parts engagable with said spring extension when the latter is adjacent said low parts, whereby turning of said cam upon said operating lever shifts said spring of the feeding pawl on opposite sides of dead center to render the feeding pawl active and inactive with respect to said ratchet teeth.

2. In a power device of the character described, a body portion, a cable winding drum having ratchet teeth journaled for rotation upon said body portion, a holding pawl pivoted to said body portion and engagable with said ratchet teeth to prevent retrograde movement of said drum, a spring associated with said holding pawl to normally maintain the holding pawl active with said ratchet teeth, a lifting element carried by said holding pawl, an operating lever swingably secured to said body portion, a feeding pawl pivotally secured to said operating lever and engagable with said ratchet teeth for driving said drum when the operating lever is swung in one direction, said lifting element of the holding pawl in the path of travel of the feeding pawl and engagable therewith when the operating lever is swung in one direction to disengage the holding pawl from said ratchet teeth, a single coil spring only attached to said pivoted feeding pawl and having a longitudinal extension, a cam rotatably mounted upon said operating lever and having an opening receiv-

ing said spring extension and a sloping cam part including high and low cam faces slidably engaging said spring extension and stops adjacent said low cam faces engagable with said spring extension, and a lever secured to said cam to turn the latter in opposite directions, whereby said spring attached to the feeding pawl is shiftable upon opposite sides of dead center with respect to the feeding pawl to render the feeding pawl active or inactive with respect to said ratchet teeth.

3. In a power device of the character described according to claim 2, wherein said cam is substantially cylindrical and cup-like and includes an annular peripheral wall, said opening for said spring extension being formed through the forward portion of said peripheral wall and said cam part including the high and low cam faces extending circumferentially around approximately one-half the circumference of said peripheral wall at the rear side of the same and said stops are disposed in diametrically opposed relation on said peripheral wall.

4. In a power unit of the character described, as a sub-combination, a rotary cable winding drum having spaced ratchet teeth on its periphery, an actuating lever for said drum, a feeding pawl pivoted to said lever and engagable with said ratchet teeth to turn said drum when the actuating lever is moved in one direction, a cam rotatably mounted upon said lever near the feeding pawl and including an actuating part, said cam being cup-like and having an annular peripheral wall including a sloping edge cam portion extending circumferentially of the cam for substantially 180 degrees, said sloping edge cam portion having a central high part and end low parts terminating in stops on said peripheral wall, said peripheral wall having a side opening substantially opposite said high part and midway between said stops, and a coil spring having one end attached to said feeding pawl

30

35

and having an opposite end extension engaging through said side opening and bearing slidably against said sloping edge cam portion and engagable with said stops when the cam is turned in opposite directions for rendering the feeding pawl active or inactive.

5. In combination, a feeding pawl actuating lever, a feeding pawl pivotally mounted upon said lever and adapted for engagement with ratchet teeth of a drum or the like to be turned, a cup-like cam rotatably mounted upon said lever, an operating lever secured to said cam for turning the same in opposite directions, said cam having an annular peripheral wall provided with a side opening and including a sloping edge portion having a central high part substantially opposite said opening and end low parts terminating in stops, said stops being formed on said annular wall and spaced equidistantly circumferentially of the side opening, a coil spring attached to said pawl and having an end extension engagable through the side opening and extending across the cam substantially diametrically and slidably bearing upon said sloping edge portion and adapted to contact said stops when the cam is turned in opposite directions to render said pawl active or inactive, the cam shifting the spring beyond opposite sides of dead center with respect to the pawl and its pivot to render the pawl active and inactive.
